D. D. Marsh,

Invalid Bedstead.

No 78,986.

Patented June 16, 1868.

United States Patent Office.

JOHN YOUNG, JR., OF SUNAPEE, NEW HAMPSHIRE, ADMINISTRATOR OF
THE ESTATE OF DELLAVAN D. MARSH, DECEASED.

Letters Patent No. 78,986, dated June 16, 1868.

IMPROVED INVALID-BEDSTEAD.

The Schedule referred to in these Letters Patent and making part of the same.

TO ALL WHOM IT MAY CONCERN:

Be it known that DELLAVAN D. MARSH, late of Croydon, in the county of Sullivan, and State of New Hampshire, deceased, in his lifetime invented a new and improved device for raising and relieving sick and other disabled persons from a recumbent position in bed, and removing them from one bed to another, or to a chair or other place of rest or repose; and that the following is a full and exact description thereof, reference being had to the accompanying drawings, and to the letters of reference marked thereon, (the same letters representing corresponding parts in the different figures,) making a part of this specification.

The nature of the invention of said MARSH consists in providing suitable mechanism attached to the floor or platform, on which the bedstead may be firmly secured, and against which the mechanism rests, by which a sick person, or one disabled by wounds, or otherwise, may be raised either at the head or feet, or on either side, to any position desired, or removed from one bed to another, when desired.

To enable others skilled in the art to make and use the invention of the said MARSH, its construction and operation are described as follows, namely:

X is the floor or platform to which said mechanism is fastened, by means of the bed-piece U and the screws V V'. The bedstead Y, though not attached, is firmly confined in place on the floor by means of the bed-piece U, and also the bed-piece, U', fastened to the floor by the screws V' V''.

A A' are two upright supporting-bars united at the top by the cross-bar B, the upper surface of which forms a circular bed-plate, as seen in Figure 4, on which the circular plate F' rests and revolves. Friction-balls or rollers may be used between the faces of these two plates, to render their motion easier. B' is also a cross-bar or brace, uniting the supporting-bars A A'.

C is the king-bolt, which passes through the cross-bars B B', and the apertures b b' b'' in the supporting-lever D, the latter being strengthened by the steel plate H, which passes over the upper surface of the same, and laps over each end, and is fastened to the supporting-lever by screws or nails.

E E' E'' are supporting-arms, made of steel, of sufficient size and strength to bear the weight of the patient, which pass over through slots to the supporting-lever D, as seen more fully in Figure 2, and having a sliding motion in said slots.

F F', &c., are pulleys at the ends of the supporting-arms, over which the cords Z Z', &c., and J J', &c., pass, the said cords being fastened to the sockets d d', &c., at the ends of the resting-bars g g' g'', the ends of the latter reposing in said sockets.

G G' G'', one of which is shown in Figure 9, are double guide-pulleys in the pulley-frame I, over which the cords Z Z', &c., and J J', &c., pass. Separate pulleys may be used for each cord, if necessary, in the actual operation of the machine. The cords Z, Z', &c., designated on the drawings by dark lines, are used for elevating or depressing the head or feet of the patient, or lifting and removing him from one bed to another, or to a chair or other place of rest, as may be desired, and are fastened to the ends of the sockets d d', &c., and thence pass over the pulleys F F', &c., the guide-pulleys G G' G'', and thence down, and are confined to the axles of the ratchet-wheels K K' K'', which are operated by the cranks L L' L'', the said cranks and ratchet-wheels being more fully represented in Figure 5.

The cords J J', &c., designated by red lines, are designed for lifting the patient on either side, and are also confined to the sockets d d', &c., and thence pass over the pulleys F F', &c., the guide-pulleys G, and thence down, and are confined to the axles a a', the cord J to the axle a, and the cord J' to the axle a', operated by the crank R, as seen in Figure 7. The cords J J', &c., are united at the points i i', &c., thence each forming a single cord down the axles a a', by which device either side, of the patient is lifted equally. If it is desired to raise the left side, the crank R is turned from you; if the right side, the same crank is turned towards you. The crank is kept from turning back either way, as the united cords, J J', may be respectively operated by the pin h, as seen in Figure 1.

M is a plate, connecting the cranks L L' L'', f f' f'' being the apertures through which the axles of the cranks pass, and for the purpose of operating all of them simultaneously and with equal motion, and is more fully shown in Figure 6.

N is a plate, to which are attached the catches P P' P'', which play into the teeth of the ratchet-wheels K K' K''. The latter being fastened to the axles of the cranks L L' L'', the said catches, by means of the pins and slots e e', permitting a lateral motion of the plate N, may be put in or out of gear with said ratchet-wheels, when either of the cranks L L' L'' is to be turned singly.

O are apertures for pins used to keep the plate N in place after being moved laterally either way.

W is a rebate or groove in the bed-piece U, in which the bolts T T' play.

S S' are bolts with a bent head, lapping over the bed-piece U, the office of said bolts being to confine the upright posts A A' to the bed-piece U, at the same time permitting them, and the apparatus which they support, to be moved laterally either way, as may be desired, in operating said machine, that is, for removing the patient to a bed placed on either side of the bed Y. S'' S''' are also bent-headed bolts, confining the supporting-bars A A' to the end of the bedstead Y. Friction-rollers may be placed under the lower ends of the supporting-bars A A', to render their motion easier. The resting-bars g g' g'' may be made wider, in the form of lattice-work, or in oval form, as shown in Figure 8, if it is desirable to have a more equal support for the patient in lifting and removing him.

In Figure 3, the supporting-lever D, and the parts connected therewith, are more fully shown, and in different positions, namely, over the bed on which the patient reposes, on the side of it, and behind it.

The materials for construction may be suitable wood or metal, as may be found necessary or preferable.

The machine above described is operated as follows, namely: When the patient is placed on the bed Y, the resting-bars g g' g'' may be placed under him, or under the bed on which he reposes, there to remain, and to be used as occasion may require, or they may be removed and replaced when necessary. If it be required to elevate or depress his head, or the upper part of his body, the cords Z Z' may be attached to the sockets d d' of the bar g, and operated by the crank L''. If it is desired to elevate or depress his feet or lower part of his body, the cords Z''' Z'''' may be attached to the sockets d d' of the bar g'', and operated by the crank, L. If it is desired to elevate or depress the whole body of the patient, the cords Z Z' Z'' Z''' Z'''' are each to be attached to its respective socket of the resting-bars g g' g'', and operated by all the cranks L L' L'', which are moved simultaneously by the plate M, whereby the whole body of the patient may be lifted or depressed; and if it is desired to remove him to another bed or place of repose, the supporting-bars A A' may be moved laterally to the side of the bed Y, from which the patient is to be transferred, and the supporting-lever D, turning upon the bed-plate B, may be swung over the bed or chair to which he is to be transferred. The patient may then be let down and deposited upon the second bed or chair, by the reverse action of the cranks L L' L'', and the mechanism operated thereby. The bed to which the patient has been transferred may then be placed upon the floor or platform X, in place of the bed from which he was taken. If it is desired to change the position of the patient, or elevate him on the left side, the cord J, attached to the axle a, is to be operated by the crank R, turning it from you. If to elevate him on the right side, the cord J', attached to the axle a', is to be operated by the crank R, turning it towards you. If it is desired to shorten or lengthen the arm of the supporting-lever D, it may be moved forwards or backwards in the slot or mortise in the pulley-frame I, through which it passes, and confined by the king-bolt C in either of the apertures b b' b'' shown in fig. 2, the king-bolt C passing through the aperture b in the bed-plate B, as seen in fig. 4.

Having above described the construction and operation of the said improved device, invented as aforesaid, by the said DELLAVAN D. MARSH, deceased, what is claimed and desired to be secured to his legal representatives by Letters Patent, is—

1. The combination of the resting-bars g g' g'' and sockets d d', &c., the supporting-lever D, the supporting-arms E E' E'', the pulleys F F', the pulley-frame I, and pulleys G G' G'', and circular revolving plate F², the bed-plate B, the king-bolt C, the supporting-bars A A', the bed-pieces U U', the cords Z Z', the ratchet-wheels K K' K'', and cranks L L' L'', the cords J J', &c., and the axles a a', and crank R, combined, arranged, and operating substantially, and for the purposes above described.

2. The combination of the resting-bars g g' g'' and sockets d d', the supporting-lever D, the supporting-arms E E' E'', and the pulleys F F', the pulley-frame I, and pulleys G G' G'', the circular revolving plate F², the bed-plate B, the king-bolt C, the supporting-bars A A', the bed-pieces U U', the cords Z Z', the ratchet-wheels K K' K'', and cranks L L' L'', arranged and operating substantially as above described.

3. The combination of the resting-bars g g' g'' and sockets d d', the supporting-lever D, the supporting-arms E E' E'', the pulleys F F', the pulley-frame I, and pulley G, the circular revolving plate F², and bed-plate B, the king-bolt C, the supporting-bars A A', the bed-pieces U U', the cords J J', the axles a a', and crank R, arranged and operating substantially as above described.

JOHN YOUNG, JR.
